(57) **CLAIM**

The ornamental design for a saw handle, as shown and described.

DESCRIPTION

FIG. 1 is a perspective view of a saw handle;
 FIG. 2 is a right side view of saw handle;
 FIG. 3 is a left side view of a saw handle;
 FIG. 4 is a front view of a saw handle;
 FIG. 5 is a rear view of a saw handle;
 FIG. 6 is a top view of a saw handle; and,
 FIG. 7 is bottom view of a saw handle.

The broken line showing of the blade is provided for purposes of environment and form no part of the claimed design. The portions of the saw handle described by broken lines, form no part of the claimed design.
